UNITED STATES PATENT OFFICE

GEORGE S. CHILES, OF CHICAGO, ILLINOIS, ASSIGNOR TO DALMAN, CHILES COMPANY,
A CORPORATION OF DELAWARE

RAILWAY-CAR TRUCK.

Original application filed May 15, 1922, Serial No. 561,132. Now Patent No. 1,493,961, dated May 13, 1924. Divided and this application filed April 23, 1924. Serial No. 708,359.

To all whom it may concern:

Be it known that I, GEORGE S. CHILES, a citizen of the United States of America, and a resident of Chicago, Illinois, have invented a certain new and useful Improvement in Railway-Car Trucks, of which the following is a specification.

This application is a division of my prior copending application Serial No. 561,132, filed May 15, 1922, now Patent No. 1,493,961, granted May 13, 1924, and relates to a railway car truck of the type disclosed and claimed in my United States Patent No. 1,457,345 granted June 5, 1923, and in said copending application.

In the type of truck referred to, I support the springs upon the tension member of the side frame between the columns, but incline the tension member upward toward the ends of the side frame from points inside of the columns and directly beneath the spring assemblage. I dispose the spring seat upon different levels. The central part of the spring seat I place at the lowermost level on the central part of the tension member and the outer or end parts of the spring seat are wholly or partly upon the upwardly inclining parts of the tension member. The modifications in the form of the bolster and the other elements of the truck which grow out of this form of spring seat form no part of the invention claimed herein, but examples of the complete structure are fully described in my Patent No. 1,457,345 above referred to. The invention claimed herein relates to an improved form of spring plank for use in combination with the forms of truck side frame referred to above.

Figure 1 of the drawing is a plan view partly in section showing one end of my improved spring plank and the central part of the tension member of the side frame.

Figure 2 is an elevation view from the outer side of the side frame of the structure shown in Figure 1, the view being partly in section.

Figure 3 is a sectional elevation transverse of the side frame upon the central longitudinal plane of the spring plank.

Figure 4 is a view similar to Figure 3 of a modified form.

Figure 5 is a plan view of the spring plank shown in Figure 4.

In my improved construction, the entire

spring assemblage rests on the spring plank. 55 The tension member inclines upwardly from its central part toward the columns 10 and takes the form of a channel from the web of which side flanges 2, extend upwardly. Between the columns 10 a horizontal web 3 60 joins the side flanges 2, and at its ends merges with the web 1. Openings 4 and 5 lighten the structure and permit the removal of the core. Projecting upwardly from the web 3 adjacent the columns 10 are elevated 65 seats 6 for the outer or end springs of the spring assemblage, the upper surface of web 3 between the seats 6, forming a support at a lower level for the central springs. The elevated seats 6 may be integral with 70 the tension member or otherwise constructed.

The spring plank A takes the form of a channel. The flanges 7 continue through to the ends of the plank passing between the end or outer springs 8 and the central group 75 of springs 9 and 10 and being curved inwardly between the springs 9, 10 in order to permit closer spacing of the springs 8.

The outer end of the spring plank as shown in Figures 1, 2 and 3 is depressed at 11 to 80 conform to the upper surface of the tension member which has raised edge flanges 12, formed by the extension of the side flanges 2 above the web 3. At the upper edges of the flanges 7 adjacent the end of the spring 85 plank the horizontal extensions 13 of the spring plank project outwardly over and rest upon the elevated spring seat sections 6, 6. Dowels 14 upon the spring seat are engaged by openings in the spring plank and 90 by the springs.

In the construction shown in Figures 4 and 5, the side flanges 2', 2' of the tension member are closer together than the corresponding flanges 2, 2 of the form shown in 95 Figures 1, 2 and 3 and the web 3 projects transversely of the side frame beyond the flanges 2', 2' to afford sufficient width for the seating of the springs. In the form shown in Figures 4 and 5 the edge flanges 100 or beads 12 of the form shown in Figures 1, 2 and 3 have been omitted leaving the upper surface of the web 3' flat from edge to edge, thus simplifying the form of the spring plank. As appears in Figures 4 and 5 the 105 spring plank A' is formed with its web 15 flat from end to end, the dowels 16 upon the spring seat serving to accurately posi-

tion the side frames, spring plank and a spring plank resting upon said tension member between said columns and having integrally formed therewith spring supporting seats on different levels whereby an increased number of standard springs may be used between the bolster columns spaced apart a given distance.

5 I claim as my invention:

1. In a railway car truck, side frames each comprising a compression member, a tension member, columns and a spring seat between said columns, said spring seat having a central section and outer sections at a higher level than said central section, and a spring plank having at each end a central section and outer sections at a higher level than the central section said central and outer sections of said spring plank being supported on said central and outer sections of said spring seat.

10 2. In a railway car truck, the combination of a side frame including tension and compression members and bolster columns, and

15 3. In a railway car truck, the combination of an integrally formed side frame including tension and compression members and bolster columns, and a spring plank having integrally formed spring seats at different levels and resting upon said tension member between said bolster columns whereby the distance between the bolster columns may be minimized where more than four springs are used.

20 Signed at Lima, Ohio, this 19th day of April, 1924.

GEORGE S. CHILES.
